RAIL ANCHOR

George Loop Moore and James Robert Steele,
Owego, N. Y.

Application September 3, 1931. Serial No. 560,898

15 Claims. (Cl. 238—315)

Our invention relates to rail anchors and particularly to anchors for resisting the longitudinal creeping of railroad rails.

One of the objects of our invention is to provide a one-piece anchor which is easily applied to a rail, which efficiently grips the rail base flange and which cooperates with a stationary member of the roadbed to resist the creeping of the rail.

10 Another object of our invention is to provide a rail anchor which is applied to a railroad rail by distortion and which effectively grips the rail base flange due to the tendency of the anchor to resume the condition from which it was distorted when applied to the rail.

A further object of our invention is to provide a one-piece rail anchor which is adaptable to rails having base flanges of different widths.

Another object of our invention is to provide 20 a rail anchor which will check the longitudinal creeping of the rail in either direction of traffic. The novel features of our invention will be more fully understood from the following description and claims taken with the drawing in which:

25 Fig. 1 is a top plan view of our improved anchor;

Fig. 2 is a side view of the anchor shown in Fig. 1;

30 Figs. 3 and 4 are end views of the anchor; and Fig. 5 is a side view of a railway track structure with our improved rail anchor.

Referring to the drawing: 14 designates a rail, 35 15 a cross tie, 17 a railroad spike and 18 the rail anchor which is the subject of our invention.

35 The anchor 18 comprises end members 19 and 20, respectively, and a connecting member 21 which is adapted to bridge a railroad tie.

The end members 19 and 20 comprise U-shaped members having notches in each leg thereof 40 adapted to receive the flange of a rail. The member 19 has portions 22 and 23 for engaging the upper surface of the rail base flange and portions 24 and 25 for engaging the under surface of the rail base flange. The member 20 has 45 portions 26 and 27 for engaging the upper surface of the rail base flange and portions 28 and 29 for engaging the under surface of the rail base flange. The connecting member 21 is preferably provided at its ends with compensating members 50 30 and 31, respectively. The connecting member 21 is also provided with a pocket 32 for receiving the head of a spike to retain the anchor in its assembled position. The sides of the pocket also function to engage the side of the spike head 55 upon the tendency of the rail to creep longitudi-

nally in either direction of traffic, so as to retain the anchor in its operative position to resist the creeping of the rail.

The anchor is applied to a rail by hooking either end of the anchor over the flange of the rail. 60 If the end 20 is hooked over the flange a blow is struck at the side thereof so that the rail engaging portions 26, 27, 28 and 29 will be brought into gripping engagement with the flange. The connecting member 21 is then brought over the 65 head of the spike 17 to the position shown in dotted lines in Fig. 5. Pressure is then applied to the member 21 near the end 19 such as by placing the foot thereon and striking a downwardly and inwardly directed blow at the point 70 indicated by the arrow in Fig. 5. This will cause the rail engaging members 24 and 25 to pass downwardly beyond the lower edge of the rail base flange.

As soon as the members 24 and 25 pass beyond the lower edge of the rail base flange the end 19 will spring inwardly and thus cause the members 24 and 25 to engage the bottom of the rail base flange. The anchor may be brought into more effective engagement with the rail flange 75 by a blow on the sides of the ends 19 and 20 of the anchor. The anchor is now in its operative position as shown in full lines in Fig. 5.

When the anchor is in its operative position on the rail any tendency on the part of the rail to 80 creep longitudinally due to the passage of traffic thereover in either direction is restrained owing to the double grip on the rail base flange by each end of the anchor due to the anchor being held in its operative position with respect to the roadbed by its engagement with the head of the spike 85 17.

The passage of traffic over the track moves the rail upwardly a short distance off the tie and therefore causes the spikes to move out of the 90 tie a short distance. The anchor 18 which is connected to the rail will also be moved upwardly with the rail and spike. When the traffic is directly over the tie the load thereof will cause the rail to move downwardly into engagement with 95 the tie and the ends of the anchor also will be carried downwardly therewith. As the connecting member 21 of the anchor is over the spike head which has previously been raised out of the tie the load on the rail would be transmitted 100 through this member to the spike unless some provisions were made on the anchor to overcome this condition. To obviate this condition and also the waving action of the rail we have 105 provided the anchor with compensating members 110

30 and 31 which are adapted to flex under a load applied to the ends of the anchor from the rail due to the passage of traffic thereover and therefore permit the ends of the anchor to be moved 5 downwardly without the full load on the rail being transmitted through the connecting member 21 to the spike 17.

These compensating members are particularly adaptable with an anchor of the type herein described 10 as the double grip on each end of the anchor prevents the ends of the anchor from changing their position longitudinally of the rail.

From the foregoing description it will be obvious to those skilled in the art that we have devised 15 an improved one-piece anchor which is simple in construction, which is easily applied to the rail base flange and which efficiently grips same to check the tendency of the rail to creep in either direction of traffic. Our device is particularly adaptable to rails having base flanges 20 of different widths as it grips only one side of the flange of a rail, and therefore its gripping ability is not affected by the changes in widths of base flanges.

25 While we have shown our invention in but one form, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended 30 claims.

Having thus described our invention what we 35 claim as new and desire to cover by Letters Patent is:

1. An anchor comprising a plurality of rail 40 engaging members, a connecting member to pass over a spike head, and a compensating member for said anchor.

2. A rail anchor comprising end members 45 adapted to engage the flange of a rail, a connecting member for said end members adapted to bridge a tie and compensating means for said connecting member adapted to permit said connecting member to flex from its normal position.

3. A rail anchor comprising spaced members 50 adapted to engage one edge of a rail base on opposite sides of a tie, a connecting member for said spaced members adapted to bridge the tie and engage the upper surface of a railroad spike, and compensating means adapted to restrain a load transmitted to said anchor from being transmitted to said spike.

4. A one piece rail anchor comprising a pair 55 of end members adapted to engage one flange of a rail and a connecting member for said end members, each of said end members comprising a U-shaped member having shoulders on the legs thereof adapted to engage one flange of a rail at a plurality of points on one side of a railroad tie.

5. A one piece rail anchor comprising a pair 60 of U-shaped end members, a body member, and a compensating member intermediate the body member and the U-shaped members.

6. In combination with a railway track structure, a roadbed, a rail mounted thereon, a spike 65 for said rail, said rail and said spike being capable of vertical movement, an anchor for restraining the longitudinal creeping of the rail, said anchor comprising rail flange engaging members, a connecting member for said rail

flange engaging members engaging the head of said spike, and compensating means on said anchor adapted to flex under a load transmitted to said anchor from the rail to permit the ends of the anchor moving downwardly independently of the connecting member. 80

7. A rail anchor comprising rail flange engaging members adapted to engage a rail on opposite sides of a tie, a connecting member for said end members, and compensating means adapted to permit the rail flange engaging member to move vertically independently of the connecting member. 85

8. A rail anchor comprising depending end members having rail engaging members thereon adapted to engage one flange of a rail base on opposite sides of a tie, an upturned member, having a rail engaging member formed thereon, connected to each of said depending end members, and a connecting member for said end members. 90

9. A rail anchor comprising U-shaped end members adapted to engage one flange of a rail at a plurality of points on either side of a tie, connecting means for said end members adapted to engage a railroad spike, and compensating means for said anchor whereby the end members may move without changing the position of the connecting member adjacent the spike. 100

10. A rail anchor having a pair of spaced rail 105 base engaging portions on each end thereof, an intermediate spike head engaging portion, a portion connecting each adjacent rail base engaging portion, and a resilient loop member connecting said intermediate portion at each end to one of 110 said pair of portions.

11. A rail anchor having an intermediate portion for engaging a spike head, and a sinuous portion at each end thereof to constitute a rail base 115 engaging portion.

12. A rail anchor having an intermediate portion for engaging a spike head, and an upwardly extending loop portion extending into a downwardly extending loop portion at each end of the first mentioned portion, each of the latter loop 120 portions being formed to provide a pair of spaced rail base bearing portions.

13. A rail anchor having a body portion, and end portions for gripping a rail flange at a plurality of points at each side of a railroad tie, each 125 end portion comprising a pair of leg portions spaced longitudinally of the rail and each leg portion being provided with a shoulder for engaging the rail flange.

14. A rail anchor comprising a body portion 130 and end portions, said body portion adapted to pass over a railroad tie and each of said end portions comprising a pair of members having shoulders for engaging the flange of a rail base at a plurality of points longitudinally of the rail 135 at each side of the tie.

15. A one piece rail anchor comprising a tie bridging member, a U-shaped member adjacent one end of said tie bridging member, said U-shaped member having recesses in each leg thereof adapted to receive the flange of a rail base and means adjacent said recesses adapted to grip the rail base flange at a plurality of points longitudinally thereof at one side of the tie, and a rail base flange engaging member connected to 140 the other end of the tie bridging member. 145
